TELEPHONE SYSTEM

Harry P. Mahoney, Oak Park, Ill., assignor to Automatic Electric Laboratories, Inc., Chicago, Ill., a corporation of Delaware

Application January 8, 1944, Serial No. 517,538

11 Claims. (Cl. 179—27)

This invention relates to telephone systems and its purpose is to provide a method and means for effecting the gradual conversion of a telephone system of the manual type to one of the automatic type, and providing a direct connection between manual and automatic portions of a partially converted system, without interruption in the service or inconvenience to the subscribers and without the necessity of installing any expensive or complicated temporary or auxiliary equipment.

The problem of converting a manual telephone system to an automatic system, while maintaining service in the entire system while it is partly manual and partly automatic, is complicated by the fact that an automatic system is commonly operated on a voltage much higher than that employed in a manual system and by the further fact that the polarities of the line conductors in an automatic system are reversed as compared with the usual manual system. These factors present substantial difficulties, particularly when the conversion from one system to the other extends over a considerable period of time during which both the manual and the automatic portions of the system are in operation and both types of lines are to be interconnected.

Heretofore, it has been the practice, where such a conversion became necessary, to install special and temporary auxiliary equipment including a call indicator switchboard comprising indicators adapted to notify the operators at that position of the numbers being called by automatic lines, thereby enabling the operator to extend the call manually to the called subscriber's line. Where the call originates on a manual line, the extension of the call to the automatic lines has involved the provision of special operator positions at the automatic office for completing the connections extended thereto by the manual operators.

The present invention provides a solution for the above-mentioned difficulties without the use of substantial auxiliary or temporary additional equipment by furnishing a system according to which the manual telephone system is directly connected to the automatic system as the automatic system is progressively installed and the two systems are coordinated for conjoint operation by changes which are confined almost entirely to the manual equipment so that when the automatic system has been entirely completed and supplants the manual system, the automatic system requires only minor alterations to adapt it to the usual or standard automatic operation,

so that there is no impairment or interruption of service and no necessity for changing telephone numbers in any part of the system.

The primary object of the present invention is to provide an improved method of effecting the gradual conversion from manual to automatic service according to which a system comprising manual equipment and automatic equipment is arranged for interconnection and the extension of calls in both directions between the manual and the automatic portions of the systems by changes which consist, primarily, in reversing the polarity of the lines of the manual system to agree with the polarity of the lines of the automatic equipment and, at the same time, making a minor change in the operating voltage of the automatic system to approximate or harmonize with the operating voltage of the manual system. A further object is to provide a manual telephone system comprising cord circuits of either the three conductor type or the two conductor type, or both of these types, which is directly connected with an automatic telephone system and in which the polarity of the lines and the operating voltages of the different parts of the composite system are altered so that, with a minimum of additional equipment, telephone calls originating in any part of the system may be extended to subscriber stations in the other parts of the system to provide satisfactory service without the attention of special operators. Other objects relate to various features of the improved system whereby a gradual and economic transition may be made from manual service to automatic service while providing a uniformly good service during the period of transition.

The nature of the invention will be understood from the following specification taken with the accompanying drawings in which a telephone system embodying the present invention is illustrated. In the several figures of the drawings, taken together, there is illustrated, somewhat diagrammatically, a complete system which is partly of the manual type and partly of the automatic, the manual portion of the system being shown in Figs. 1 and 4 and the automatic portion in Figs. 2, 3 and 5. It is assumed that in this illustrated system the conversion from manual to automatic service is in the process of transition and that the necessary changes have been made to permit the manual and the automatic portions of the system to be operated to permit calls to be extended in either direction between said portions of the system during the period when both portions of the system are operating.

During this period calls may, of course, be completed locally in each exchange or between different exchanges of the manual system and the plan of transition contemplates a gradual conversion to automatic operation with the possible addition of lines either to the manual or to the automatic portion of the system, depending upon economic and operating conditions and facilities. Also, the automatic system is arranged to complete connections from lines in the automatic system to lines in the manual system without the aid of an operator in the manual system.

General description

Before describing the operation of the system or the details of the method of conversion employed, some of the principal features embodied in different parts of the telephone system will be referred to.

The manual portion of the telephone system comprises two divisions, shown in Figs. 1 and 4, that portion of the system illustrated in Fig. 1 including three-wire cord circuits, such as the cord circuit 30, and that part of the system illustrated in Fig. 4 comprising two-wire cord circuits, such as the cord circuit 40. This manual system includes a plurality of subscribers' sub-stations, such as the stations M and MA, which are connected by the subscriber lines L100 and L400, respectively, with the contacts A of the main distributing frame MDF. These contacts A are adapted to be connected by jumpers with the associated contacts B of the main distributing frame and, in the portion of the circuit shown in Fig. 1, the contacts B are connected by the line 100a with the contacts D of the intermediate distributing frame IDF-1. Similarly, the contacts B shown in Fig. 4 are connected by the line 400a with contacts D of the intermediate distributing frame IDF-1. Each subscriber's line, such as the line L100, has associated therewith an individual manual line circuit, such as the line circuit 105, and each subscriber's line of the other division of the manual system, such as the line L400, has associated therewith an individual manual line circuit, such as the line circuit 405. Each line circuit 105 includes a cutoff relay R110 and a line relay R115. Similarly, each line circuit 405 includes a cutoff relay R410 and a line relay R415.

The contacts D of the intermediate distributing frame IDF-1, which are shown in Fig. 1, are adapted to be connected by jumpers with the contacts E which are connected by lines, such as the line 100b, with jacks, such as the Jack 101, adapted to form a connection with the plug 102 terminating the three-wire cord circuit 30. Similarly, the contacts D of the intermediate distributing frame IDF-1, which are shown in Fig. 4, are adapted to be connected by jumpers with other contacts E connected by lines, such as line 400b, with jacks, such as the jack 401, adapted to form a connection with a plug 402 terminating the two-wire cord circuit 40. The terminals D of the intermediate distributing frame IDF-1, shown in Fig. 1, are also connected by the line 100a with jacks, such as the jack 158, adapted to be connected with the plug 155 by which the operator causes outgoing calls from the three-wire cord circuit 30 to be extended over the line 100a to a called subscriber's line, such as the line L100. In a similar manner, the contacts D of the intermediate distributing frame IDF-1, which are shown in Fig. 4, are connected by the line 400a with the multiple jacks, such as jack 456, adapted to be engaged by the plug 455 by

which the operator causes outgoing calls from the two-wire cord circuit 40 to be extended over the line 400a to a called subscriber line, such as the line L400.

The three-wire cord circuit 30 comprises the answering plug 102, the call plug 155 and associated apparatus and circuit connections including the sleeve relays R120 and R150, the supervisory relays R125 and R130, the ring relay R135, a control relay R140, a ring cutoff relay R145, a ringing generator 175, the operator's headset 181 and the talk key 180. A call originating in the manual system shown in Fig. 1 may be extended through the multiple jack 158 and over the line 100f to subscriber stations of the division of the manual system shown in Fig. 4.

The two-wire cord circuit 40, shown in Fig. 4, comprises the answering plug 402 and the call plug 455, together with associated apparatus and circuit connections including the sleeve relays R420 and R440, the supervisory relays R425 and R430, the operator's headset 481 and the talk key 480. The portion of the manual circuit shown in Fig. 4 also includes the multiple jack 458 by which a connection may be made with a plug 455 and through the line 100g, a cordless B board 440, and a line 100f to subscribers' lines, such as the line L100, terminating at the switchboard shown in Fig. 1.

As the manual system shown in Figs. 1 and 4 is organized, prior to any changes which are made in the connections for the purpose of conversion, the circuits are connected to battery by the lead 117 and to ground by the lead 118 by connections which are illustrated by dotted lines in Figs. 1 and 4. When the system operates with the dotted line connections, it customarily operates on a comparatively low voltage, such as a voltage of 24, which is common commercial practice. When the manual system is to be altered for operation in connection with a system of the automatic type, the connections to battery and ground are reversed, as indicated above, but the same operating voltage is retained in this manual portion of the system. As shown in Figs. 1 and 4, the connections have been reversed, as indicated by full lines, so that the terminals which were previously connected to battery and ground, respectively, are now connected to ground and battery, respectively. The necessity for making this reversal of the battery and ground connections in the manual system when a connection is made with the automatic system arises from the fact that the polarities of the tip and sleeve conductors are normally reversed with respect to the polarities of the corresponding conductors in the automatic system. In the customary operation of a manual system, with the sleeve of a busy called line connected to battery by way of the corresponding sleeve relay R120 in the associated cord circuit and the tip of the calling cord circuit connected to ground by way of its associated supervisory relay R130, the test for a busy condition of such a line is made by momentarily connecting the tip of the associated calling plug with the sleeve of the multiple call jack of the busy called line, the busy condition being indicated by a busy click which is produced in the operator's headset as a result of opposite potentials on the sleeve and the connected tip. In the operation of an automatic system, on the other hand, the busy condition of a line is indicated by the presence of ground on the conductor corresponding to the sleeve conductor so that, if a manual and an automatic system were connected together without any re-

versal of polarity, the usual busy test procedure would bring together two parts having ground connections or two parts having battery connections, so that a false busy test would be made and no true indication of the busy condition given.

The automatic portion of the system shown in Figs. 2, 3 and 5 comprises a number of automatic subscriber stations, such as the station P, to which connections are made through automatic apparatus and lines including the link 200 comprising a finder 210 and a selector 220, together with a distributor 270, a connector 300, a trunk circuit 530, a selector 535, and a plurality of line circuits, such as the line circuit 305, and a plurality of lines, such as the line 300_a, connecting the line circuits with the finder banks by way of an intermediate distributing frame IDF-2 through which connections are made with the finder 210. The automatic system also includes a plurality of lines, such as the connecting line 100d, for connecting the automatic system through the intermediate distributing frame IDF-2 with the connecting line 100e which extends to the main distributing frame MDF of the manual system shown in Fig. 1. There is also included in the automatic system a plurality of lines, such as the connecting line 400d, extending from the connector bank of the connector 300 to contacts G of the intermediate distributor frame IDF-2 through which a connection is made with the connecting line 400e extending to the main distributing frame MDF of the manual exchange shown in Fig. 4.

All of the parts of the automatic system referred to above are installed as a part of the original automatic equipment and function as such throughout the time that the automatic system is being used in connection with the manual system for transmitting calls in both directions. In addition to these parts of the automatic system, other automatic apparatus and other lines are originally installed as a part of the automatic system but begin to function only as portions thereof are brought into use as the manual system is progressively converted into an automatic system. This additional equipment, which gradually comes into use as a part of the automatic system during the process of conversion, includes a plurality of line circuits, such as the line circuit 201, and a plurality of line circuits 501.

When the automatic system is originally installed, for intended use in conjunction with the manual system, it also includes a plurality of temporary connecting lines 300a which extend from the jacks 159 of the manual system to terminals F of the intermediate distributing frame IDF-2 in the automatic system. Calls are extended over these lines 300a from the manual system to the automatic system during the period of conversion and when the conversion has been completed these lines 300a may be removed. Also, during the period of conversion, the system comprises the jacks 459, adapted to be connected with the plugs 455 of the manual system, these jacks being connected by the lines 531 with the trunk circuit 530 from which lines 532 extend to the selector 535. When the conversion from manual to automatic service has been completed for the manual system shown in Fig. 4, the jacks 459, lines 531 and 532, and trunk circuit 530 may be discontinued or removed.

In addition to the reversal of the polarities in the manual system which is effected for purposes of conversion to agree with the polarities of the

automatic system, referred to above, it is also necessary during the period of conversion to alter the voltages of the busy relays of the connectors 300 and the cutoff relays of the line circuits such as the line circuits 201, 501 and 305 to cause them to agree with the voltages of the manual system. During the period of conversion, the battery connections are made as shown by full lines to the conductors 117 shown in the lower part of Fig. 3 and in the lower part of Fig. 5, thereby causing the busy relays and cutoff relays just referred to to operate on a low voltage, such as the customary voltage of 24, for example. When the conversion has been completed so that the entire system is automatic, these battery connections are shifted, as shown at 118 in Figs. 3 and 5, to connect the terminals of these busy and cutoff relays to a high voltage battery, such as one having a voltage of 48, this being the standard voltage on which other parts of the automatic system operate throughout the period of conversion, as well as when the system has been entirely converted.

In the drawings, the low voltage battery connections have been designated LV and the high voltage battery connections have been designated HV. The tip, ring and sleeve conductors of the manual system have been marked T, R and S, respectively. The conductors of the automatic lines which correspond to the tip and ring conductors of the manual system have also been marked T and R, respectively, and the third or control conductor has been marked C.

In order that the operation of the invention may be more fully understood, the manner of completing various telephone connections, including the extension of calls from one manual station to another and of calls involving the use of both the manual and the automatic portions of the system, will now be described. All of these operations are described on the assumption that the above-described changes have been made for permitting the conjoint use of the manual and the automatic portions of the system.

Call from substation M to substation MA

Assuming that the manual and the automatic systems have been interconnected as described and that the battery polarity alterations have been made in the manual system as indicated in full lines, a subscriber at the manual substation M, desiring to call the substation MA, lifts his telephone, which causes a loop, including the line conductors of the line L100, to be completed at the substation M. The completion of the loop at the substation M causes the line relay R115 to operate over a circuit from ground at contacts 111 by way of the tip conductor of the lines 100c, 100a, and L100, through the loop at substation M, over the ring conductors of the lines L100, 100a, and 100c, the contacts 112 and through the winding of the line relay R115 to battery. The line relay R115 operates over this circuit to complete, at contacts 116, an obvious circuit for operating the answer lamp signal 103. To answer the call, the operator inserts the answering plug of one of the cords, such as the plug 102 of the cord circuit 30, into the jack 101 which is associated with the signal 103. When the sleeve of the plug 102 contacts the sleeve of the jack 101, a circuit is completed for energizing in series the sleeve relay R120 and the cutoff relay R110. This circuit can be traced from ground at the lead 118, through the winding of the sleeve relay R120, the sleeves of the plug 102 and jack 101, and the winding of the cutoff relay R110 to LV battery on the con-

ductor 117. In operating, the cutoff relay R110 interrupts, at contacts 111 and 112, the circuit for energizing the line relay R115 which then restores to open, at the contacts 116, the circuit for illuminating the answer lamp signal 103. The sleeve relay 120, in operating, completes, at the contacts 122 and 123, an obvious circuit for connecting the operator's headset across the tip and ring conductors of the cord circuit, this circuit including the normally closed contacts 153 and 154. The supervisory relay R125 is also operated over the line loop when the plug 102 is inserted into the jack 101. This circuit may be traced from ground at the lead 118, by way of the upper winding of the supervisory relay R125, the ring conductor and ring contacts of the plug 102 and jack 101, over the loop at the substation M by way of the line L100, the tip conductors of the jack 101 and plug 102, and the lower winding of the supervisory relay R125 to battery upon the lead 117. In operating, the supervisory relay R125 opens, at the contacts 126, a circuit for energizing a supervisory lamp 104. With the operator's headset 161 connected across the tip and ring conductors of the cord circuit, which conductors are extended to the substation M through the associated capacitors 141 and 148 and the plug 102 and jack 101, the operator is in communication connection with the calling line L100 and obtains the number of the desired line to be called. Also, when the plug 102 is inserted into the jack 101, the multiple jack 158 which is associated with the line L100 is marked as busy by the ground potential which is applied to the sleeve conductor through the sleeve relay R120 and over the line 100a. Ground upon the sleeve of the line 100a therefore marks all of the multiple jacks associated with the line L100 as busy. In addition, ground potential is also applied to the sleeve conductor of the connecting lines 100e and 100d from the sleeve of the jack 101, which ground upon the sleeve conductor 379 marks the connecting line 100d associated with the line L100 as busy in the connector banks of the connectors, including the connector 300.

To extend the call to the substation MA, the plug 155 is inserted into the multiple jack 158, which is connected by the lines 400f and L100 to the substation MA. In inserting the plug 155 into the jack 158, ground potential is applied through the winding of the sleeve relay R150 to the sleeve of the jack 158 and to the sleeve conductor of the line 400f. Ground upon the sleeve conductor of the line 400f marks the line L400 as busy in all the multiple jacks associated with this line in both the switchboards, and the multiple jack 466 has its sleeve grounded also by connection with the sleeve conductor of the line 400f through the line 400a. In addition to marking the line L400 as busy at the manual switchboards, the line L400 is also marked as busy in the banks of the connectors, such as the connector 300, over the sleeve conductors of the associated connecting lines 400e and 400d. The connecting line 400e is connected in multiple with the line 400f at the A contacts of the main distributing frame MDF and is cross connected to the connecting line 400d through the F and G terminals of the intermediate distributing frame IDF-2. The cutoff relay R410 is operated from the ground potential upon the sleeve conductor of the line 400a to battery upon the lead 117, and, in operating, this cutoff relay disconnects, at the contacts 412, the line relay R415 from the line conductors of the line 400a.

The sleeve relay R150 operates in series with the cutoff relay R410 and opens, at contacts 152 and 154, the connections to the operator's headset 161. The relay R150, upon operating, also completes, at the contacts 152, a circuit for illuminating the supervisory lamp 157 which indicates to the operator that the call has not yet been answered. The automatic ringing of the substation MA is initiated by the operation of the ring relay R135, this relay being operated over a circuit including the contacts 151 and 142 when the relay R150 operates. In operating, the ring relay R135 completes, at the contacts 138 and 139, a path for projecting ringing current over the lines 400f and L400 to the substation MA. This circuit may be traced from battery upon the lead 117, through the ringing generator 175 and the ring cutoff relay R145 in series, through contacts 138 to the tip of the plug 155; and from ground upon the lead 118 through the resistor 176 and contacts 138 to the ring of the plug 155. The tip and ring of the plug 155 are connected by way of the tip and ring of the jack 158 and the tip and ring conductors, respectively, of the lines 400f and L400 to the ringer at the substation MA. The ringers respond to this ringing current, thereby notifying the subscriber at substation MA that a call is to be answered.

To answer the call at the substation MA, the telephone is lifted from its hook to complete a loop circuit over the tip and ring conductors of the lines L400 and 400f. These tip and ring conductors of the line 400f terminate upon the tip and ring of the jack 158 which has been connected to the tip and ring of the plug 155, and the ring cutoff relay R145, being connected in series relation with the loop and with the ground connected resistor 176 and being connected to battery through the generator 175, is then operated over this loop.

The ring cutoff relay R145, in responding to the completion of the loop circuit at the substation MA, operates to complete, at the contacts 146, an obvious circuit for energizing the relay R140. The relay R140 operates and completes, at the contacts 141, a locking circuit for itself, this circuit including the grounded contacts 151 which have been closed by the previous operation of the relay R150. At the contacts 142, the relay R140, upon operating, interrupts the circuit for energizing the ring relay R135. The ring relay R135 then restores to open, at the contacts 138 and 139, the circuit for projecting ringing current over the lines 400f and L400 extending to the substation MA. Also, the ring relay R135, in restoring, completes, at the contacts 137 and 139, connections between the tip and ring conductors of the calling end of the cord circuit with the tip and ring conductors of the called end of the cord. Further, when the call at substation MA is answered to complete the loop circuit at that station, the supervisory relay R130 is operated, over substantially the same loop circuit as that described above, and interrupts, at contacts 131, the circuit for illuminating the supervisory lamp 157. The operator at the switchboard is thereby advised that the called party at the substation MA has answered the call.

With the switchboard apparatus in this condition, the call from substation M is extended by way of lines L100, 100a, 100b, answering jack 101, the cord circuit 30, the multiple jack 158, and the lines 400f and L400 to the called station

MA. It is noted that the sleeve relays R120 and R150, the supervisory relays R125 and R130 and the relay R140 remain operated while the connection remains established between the calling and called substations and until the connection is released. When the called party at the substation MA hangs up, the loop circuit extending over the lines L400 and 400_b is interrupted, thereby causing the supervisory relay R130 to restore. Upon restoration of the supervisory relay R130, the circuit for illuminating the supervisory lamp 157 is completed at the contacts 131. The operator is thus advised that the called party has disconnected and the operator may withdraw the plug 155 from the jack 158. When the calling party at substation M disconnects, the circuit extending over the lines L100, 100_a and 100_b is interrupted to cause restoration of the supervisory relay R125 which completes, at the contacts 126, a circuit for illuminating the supervisory lamp 104. The operator is thereby advised that the calling party at the substation M has disconnected and the plug 102 may be withdrawn from the jack 101. When the plugs 102 and 155 are withdrawn from their respective jacks, the ground potential applied to the sleeve conductors through their respective sleeve relays is removed, thereby causing the busy markings to the associated jacks in the manual switchboards to be removed and also the busy markings to the associated contacts in the connector banks in the automatic system. Upon removal of the plug 155 and the restoration of the sleeve relay R150, the contacts 151 are opened to interrupt the circuit for the relay R140. Also, when the plug 102 is removed from the jack 101, the circuit for energizing the cutoff relay R110 in series with the sleeve relay R120 is interrupted to cause these relays to restore. Likewise, when the plug 155 is removed from the jack 158, the relays R410 and R150 are restored to normal. The equipment of the manual system has now been restored to normal and may be used to extend other calls.

Call extended from manual substation M to automatic substation P

In explaining the connection from the manual substation M to the automatic substation P, it is assumed that the cord circuit 30 has been used to answer an incoming call from the substation M over the lines L100, 100_a and 100_b, and that the plug 102 has been inserted into the jack 101. It is also assumed that the supervisory relay R125, the sleeve relay R120, and the cutoff relay R110 have been operated, as heretofore described. To extend this call to the substation P, the plug 155 is inserted into the jack 159 which terminates the line 300_a extending to the F terminals of the intermediate distributing frame IDF-2. When the plug 155 is inserted in the jack 159, the sleeve elements thereof are grounded through the sleeve relay R150, and this ground extends over the sleeve conductor of the line 300_a to a G terminal of the intermediate distributing frame IDF-2 where the circuit divides, one branch extending to the control conductor 382 in the connector switch bank, and the other branch extending through the contacts 397 of the line relay R395 to the winding of the cutoff relay R390, and then to battery LV. Ground potential thus placed upon the control contact of the connector bank by the conductor 382 marks the line 300_d as busy to the connector 300. The cutoff relay R390 then operates, in series with the

sleeve relay R150, over the above-traced circuit to disconnect, at its contacts 391 and 392, the line relay R395 from the subscriber's line L300.

The sleeve relay R150, in operating, completes, at its contacts 151, a circuit including the contacts 142 for operating the ring relay R135 and thereby closes the contacts 136 and 138 to cause ringing current to be projected over the line 300_a. This circuit for projecting ringing current over the line 300_a may be traced from battery upon the lead 117 by way of the ringing generator 175, the winding of the ring cutoff relay R145, the contacts 136 connected to the tip elements of the plug 155, and the jack 159; and from ground upon the lead 118 by way of the resistor 176, the contacts 138 connected to the ring elements of the plug 155, and jack 159. The ringing current is thus conducted over the tip and ring conductors of the line 300_a to the G terminals of the IDF-2, which terminals are cross-connected to the F terminals of the IDF-2. Since the line L300 extends from the F terminals of the IDF-2 to the automatic substation P, the ringing current is thus transmitted to the substation P. The subscriber at the automatic substation P, in answering the call, lifts the telephone from the switchhook to complete a loop circuit which includes the tip and ring conductors of the lines L300, 300_a, the tip and ring elements of the jack 159 and the plug 155, the contacts 136, the ring cutoff relay R145, the generator 175, and battery, and the contacts 138 and the resistor 176 to ground.

As a result of completing the loop circuit at the substation P, the ring cutoff relay R145 is operated to complete, at its contacts 148, an obvious circuit for the relay R140. The relay R140 operates and completes, at its contacts 141, a holding circuit for itself, this circuit including the ground connected contacts 151 which have been closed by the operation of the relay R150. Also, in operating, the relay R140 interrupts, at its contacts 142, the circuit for energizing the ring relay R135, thus causing this relay to restore and interrupt, at its contacts 136 and 138, the circuit for projecting ringing current to the substation P. When the relay R135 restores, a circuit is completed, at the contacts 137 and 139, between the answering plug 102 and the call plug 155. The connection is now complete between the calling manual subscriber substation M and the automatic subscriber substation P through the associated lines embodied in the connection, and these lines are appropriately marked as busy by ground potential which has been applied to the sleeve conductors of each of the lines associated with the calling and called substations.

The release of the calling line is effected as described hereinbefore. The release of the called substation P is initiated when the subscriber at that station hangs up to interrupt the loop circuit which extends over the lines L300 and 300_a to the cord circuit 30 and, more particularly, to the windings of the supervisory relay R130. The supervisory relay R130 is restored when the loop circuit is interrupted and completes, at the contacts 131, a circuit including the contacts 152, to illuminate the supervisory lamp 157. Upon observing the lighted condition of the supervisory lamp 157, the operator withdraws the plug 155 from the jack 159 to remove the ground potential from the sleeve conductors of the lines 300_a and 300_d. Removal of ground from the sleeve conductors of these lines removes the busy marking to the equipment having access to these lines.

Also, upon removal of the plug 455, the sleeve relay R150 is restored to open, at the contacts 152, a circuit for illuminating the lamp 151, and at the contacts 151 a circuit for holding the relay R140 is opened.

Call from manual substation MA to manual substation M

In making a connection from the manual substation MA to the manual substation M by way of the manual switchboard shown in Fig. 4, the subscriber at the substation MA lifts his telephone to complete a loop circuit which includes the line relay R415. This circuit may be traced from ground, at the contacts 411, by way of the tip conductors of the lines 400c, 400a and L400, through the closed loop at the substation MA, the ring conductor of the lines L400, 400a and 400c, the contacts 412 of the cutoff relay R410, and the winding of the line relay R415 to battery. The line relay R415 operates and closes, at its contacts 416, an obvious circuit for illuminating the answer lamp 403 which lamp notifies the operator that a call is to be answered upon the line L400. To answer this call, a plug such as the plug 402 is inserted into the jack 401. It is noted that the plugs of the cord circuit 40 are of the type which have but two elements, including a tip element which is arranged to make contact with the tip spring of the jack 401 and a combination ring and sleeve element which makes contact with both the ring spring and the sleeve of the jack 401. When the plug 402 is inserted into the jack 401, the cutoff relay R410 is operated in series with the sleeve relay R420 of the cord circuit 40 over a circuit which may be traced from ground upon the lead 118, through the winding of the sleeve relay R420, the ring-sleeve element of the plug 402, the sleeve of the jack 401, and through the winding of the cutoff relay R410 to battery upon the lead 117. Upon operating, the cutoff relay R410 opens, at its contacts 411 and 412, the circuit of the line relay R415. The supervisory relay R425 also operates in series with the sleeve relay R420 over a circuit from ground upon the lead 118, through the sleeve relay R420, the ring-sleeve element of the plug 402, the ring spring of the jack 401, the ring conductors of the lines 400b, 400a and L400, through the loop at substation MA, the tip conductors of the lines L400, 400a and 400b, the tips of the jack 401 and the plug 402, and through the supervisory relay R425 to battery on the lead 117. The supervisory relay R425, in operating, opens, at its contacts 426, the circuit to the supervisory lamp 404. Ground potential, as supplied to the sleeve conductor through the sleeve relay R420, is effective to mark the multiple jacks 456 of the line 400a as busy. Also, the jack 158 is marked as busy by the ground potential which is applied to its sleeve by way of the sleeve conductors of the lines 400b, 400a and 400c. The control contact in the connector bank of the connector 300, which is associated with the lines L400, 400c and 400d, is also marked as busy by the ground potential which is applied from the sleeve relay R420 through the sleeve conductors of these lines.

The usual busy test upon lines in manual telephone systems is made by bringing the tip of a cord circuit into contact with the sleeve of the jack which is associated with the line to be tested. With battery potential on the tip of the cord circuit, as, for example, in the cord circuit 40, shown in Fig. 4, which has battery potential applied through the winding of the supervisory

relay R430 and through contacts 443 and 473 to the tip of the plug 455, the placing of the tip in contact with a jack sleeve which is marked as busy with ground potential produces a busy click in the receiver of the operator's headphone, due to the potential difference between the grounded jack sleeve and the plug tip. Idle lines have negative battery potential on the jack sleeve, and when tested by applying the plug tip thereto no difference in potential is encountered so no click is produced, which indicates that the associated line is idle.

When the operator moves the switch 460 to a closed position, the headset 461 is connected across the tip and ring conductors of the cord circuit 40 and a communication connection is thereby completed between the calling substation MA and the operator's headset 461, which connection includes the lines L400, 400a, 400b, the jack 401, the plug 402, the capacitors 447 and 448, and talking conductors of the cord 40 and the switch 460. The operator may then obtain the number of the desired line to be called and extend the call by inserting the call plug 455 into the jack 458, which jack terminates the line 100f extending to the cordless B board 440. The operator at the cordless B board 440 then extends the call over the lines 100f and L100 to the substation M in the usual manner.

Upon inserting the plug 455 into the jack 458, the sleeve relay R440 is operated in series with a relay in the cordless B board 440 which is similar to the usual cutoff relay in a line circuit. In operating, the sleeve relay R440 closes, at its contacts 441, a circuit including the closed contacts 436 for energizing the supervisory lamp 457, and this lamp remains lighted until the operator at the cordless B operator position 440 answers the call. When the operator at the cordless B board answers the call, the supervisory relay R430 operates in a manner similar to that in which the supervisory relay R425 operated over the line 400b. More particularly, the supervisory relay R430 operates by a circuit which extends from ground at the lead 118 to the sleeve relay R440 and then through the contacts 446 and 474, the ring-sleeve element of the plug 455, the ring spring of the jack 458, a loop in the cordless B board, the tip conductor of the cord circuit, the tips of the jack 458 and the plug 455, the contacts 473 and 443, and the supervisory relay R430 to battery on the lead 117. In operating, the supervisory relay R430 opens, at its contacts 436, the circuit for lighting the supervisory lamp 457, causing this lamp to be extinguished and thereby giving an indication to the operator attending the cord circuit 40 that the operator at the cordless B board has answered the call. After ascertaining the number of the called line from the manual operator, the operator at the cordless B board 440 tests the busy condition of the called line and if it is found to be idle completes the connection in a well known manner. In completing the call to the substation M over the line 100f, ground potential is applied to the sleeve conductor of this line by the equipment at the cordless B board 440. The sleeve conductor of the line 100f is connected, at the A terminals of the main distributing frame MDF, to the sleeve conductors of the lines 100a and 100e. The sleeve conductors of the lines 100a and 100e are effective to extend the busy ground marking to the jacks 101 and 158, and also to the control contact in the connector banks of the connector

300 by way of the line 100d associated with the called line L163.

The answering of the call at the substation M causes apparatus in the cordless B board 440 to respond, whereby the operator at this board is notified that the call has been answered. When the plug 455 was inserted in the jack 458, the sleeve of the jack 458 was grounded from the ground which was applied through the winding of the sleeve relay R440 and the contacts 446 and 474 to the ring-sleeve element of the plug 455. The grounding of the sleeve of the jack 458 marks the line 100g as busy to any operators who may test this line at any multiple connected jacks at the switchboard.

When the subscriber at the manual substation MA hangs up the receiver, the loop circuit extending over the line L400 is opened and this causes the supervisory relay R425 to restore and close, at its contacts 426, a circuit, including the contacts 421, for illuminating the supervisory lamp 404. The operator, upon observing the lighted condition of the supervisory lamp 404, is advised that the calling party at substation MA has hung up and that the plug 402 may be withdrawn from the jack 401. In withdrawing the plug 402, the circuit for energizing in series the sleeve relay R420 and the cutoff relay R410 is interrupted, causing these two relays to restore. In restoring, the sleeve relay R420 opens, at its contacts 421, the circuit for illuminating the supervisory lamp 404. The cutoff relay R410, in restoring, prepares, at its contacts 411 and 412, the circuit for energizing the line relay R415. Also, when the plug 402 is removed from the jack 401, ground potential is removed from the sleeve conductors of the lines 400b, 400a, 400f, and the connecting lines 400e and 400d. The absence of ground from the sleeve conductors of these lines removes the busy marking which was previously applied to these lines and battery potential now extends from the lead 117 through the winding of the cutoff relay R410 to the sleeve conductors of the above-mentioned lines, whereby these lines are now marked as idle.

When the called party at the substation M restores the telephone, the operator at the cordless B board 440 is advised by the usual supervisory signal that the connection may be taken down and, in turn, extends the supervision over the line 100g to the operator attending the cord circuit 40. The loop circuit, including the tip and ring conductors extending to the jack 458, is thereupon interrupted and that causes the supervisory relay R430 to restore. In restoring, the relay R430 completes, at its contacts 436, a circuit including the contacts 441 for illuminating the supervisory lamp 457. The operator attending the cord circuit 40 is thus advised to remove the plug 455 from the jack 458, and, when that is done, it removes the ground potential from the sleeve of the jack 458 and so removes the busy marking from the sleeve conductor of the line 100g. Also, upon removal of the plug 455 from the jack 458, the sleeve relay R440 is restored and opens, at its contacts 441, the circuit for illuminating the supervisory lamp 457.

Call from manual substation MA to automatic substation P

In completing a call from the manual substation MA, it will be assumed that the cord circuit 40 has been used to answer the call on the lines L400, 400a and 400b, as described above, and that the sleeve relay R420, the supervisory relay R425

and the cutoff relay R410 have been operated. It will also be assumed that the operator at the cord circuit 40 has received the number of the desired line in the automatic telephone system. To extend this call, the plug 455 is inserted into the jack 459 and ground potential at the lead 118 is thereby applied to the sleeve conductor of the line 531 extending to the trunk circuit 530, shown diagrammatically in Fig. 5. This ground potential upon the sleeve conductor marks the jacks associated with the line 531, including the jack 459, as busy. This ground potential is applied through the sleeve relay R440 to the contacts 446 of the ring key 442 and the contacts 473 of the switch 470, to the sleeve-ring element of the plug 455 and to the sleeve of the jack 459. When the ring-sleeve element of the plug 455 engages the sleeve of the jack 459, the sleeve relay R440 is operated. This circuit may be traced from ground upon the lead 118 through the sleeve relay R440, the contacts 446 and 473, the sleeve of the plug 455 and the sleeve of the jack 459 to battery potential, which is not shown, in the trunk circuit 530. Upon operating, the sleeve relay R440 completes, at its contacts 441, a circuit including the grounded contacts 436 for illuminating the supervisory lamp 457.

The trunk circuit 530 and the selector 535 are of conventional type and function to extend the call to the line 533 and to maintain a busy ground potential on the sleeve of the jack 459. More particularly, the selector 535 responds to impulses which are sent from the dial 448 in the cord circuit 40, this dial 448 being connected by way of the contacts 471 and 472 of the switch 470, to the tip and ring conductors which are connected to the plug 455. This connection extends through the jack 458 to the selector 535 by way of the line 531, the trunk circuit 530, and the line 532. The selector 535 responds to the impulses sent by the dial 448 to position its wipers upon the contacts terminating the line 533. More particularly, the impulses produced by the dial 448 are conducted by way of the contacts 471 and 472 of the switch 470, the tip and ring contacts of the plug 455, the jack 459, the lines 531 and 532, and the trunk circuit 530, to the selector 535. The selector 535 responds to the impulses of the first digit transmitted to elevate the wipers thereof to a position adjacent the row or level of contacts terminating the line 533 which extends to the connector 300. The selector 535 selects automatically an idle line which extends to one of the connectors, and, assuming that the connector 300 is the first idle connector terminated in the row of contacts selected, the line 533, comprising the conductors 274, 275 and 276, is selected to extend the connection to the connector 300.

The connector 300 is preferably of the well-known Strowger type, and operates, in the usual way, to raise the wipers 371, 372 and 373 in response to the second digit dialed, to a position adjacent the level in the connector bank corresponding to the digit dialed. In response to the third digit dialed upon the calling device 448, the wipers 371, 372 and 373 are rotated into engagement with the contacts in the connector bank terminating the line which extends to the called party, and in the present example the wipers 371, 372 and 373 are rotated into engagement with the contacts terminating the conductors 380, 381 and 382 of the line 300d. If it be assumed that the line 300d, which is associated with the subscriber's substation P, is in a busy condition, ground potential will be found upon the control conduc-

tor 382, which ground potential will cause the operation of the busy relay R330. This circuit may be traced from ground upon the control conductor 382, by way of the control wiper 373, the contacts 352 and 363, through the winding of the busy relay R330 to LV battery on the conductor 117. The busy relay R330 operates to close, at its contacts 324, a circuit, including the busy conductor 323, for transmitting busy tone over the established connection which extends to the calling substation after the operator has restored the switch 470, in a well-known manner. The original circuit for operating the busy relay R330 passed through the contacts 352 of the slow-to-release relay R350, which relay restores after a short interval to close, at the contacts 353, a holding circuit for the busy relay R330. This circuit extends from ground upon the contacts 322, by way of the contacts 332, 353 and 363, through the busy relay R330 to LV battery upon the conductor 117. It will be noted that the busy relay R330 is connected to the LV battery source which corresponds to the battery voltage which is applied to the windings of the cutoff relays in the line circuits associated with the lines extending to the connector bank. With the busy relay R330 connected to the same battery potential as the cutoff relay windings, there is no possibility of any false operation of the busy relay R330 or the cutoff relays of idle lines which terminate in the level associated with the line 300d, when the control wiper 373 comes into contact with the terminal connected in circuit with the windings of their cutoff relays when the wipers are being rotated to the contacts of a called line.

Upon hearing the busy tone, the subscriber at the manual substation MA replaces the telephone upon the hook to open the loop circuit extending to the cord circuit 40. Thereupon, the supervisory relay R425 restores to complete, at the contacts 426, a circuit including the contacts 421 for illuminating the supervisory lamp 404 which indicates to the operator at that position that the calling subscriber has disconnected and that the plug 402 may be withdrawn from the jack 401. The operator also removes the plug 455 from the jack 459, thereby opening the loop circuit which extends through the trunk circuit 530 and the selector 435 to the connector 300, causing the trunk circuit 530, the selector 535 and the connector 300 to be restored.

If it be assumed that the called line L300 is idle when called, LV battery will be connected through the cutoff relay R390 to the control terminal in the connector bank by way of the contacts 391 and through control conductor 382. The LV battery potential upon the control terminal of the line 300d short-circuits the winding of the busy relay which has one terminal connected to the same source of LV battery potential. After the slow-to-release relay R350 restores, the switching relay R360 is operated over a circuit extending from ground at contacts 322 by way of the contacts 331, the upper winding of relay R360, the contacts 351, and the wiper 373, the control terminal and conductor 382, contacts 391 and through the winding of the cutoff relay R390 to LV battery. The cutoff relay R390 is thus operated to open, at its contacts 391 and 392, the circuit of the line relay R395. In operating, the switching relay R360 completes, at its contacts 361 and 362, a circuit for conducting ringing potential to the called line L300 and for preparing the talking circuit to the called substation P. At the con-

tacts 365, the switching relay R360 connects ground potential to the control conductor 382 to mark the line 300d as busy to any other connectors attempting to call this line. The release relay R310 is operated by the line relay, which is not shown, and completes at the contacts 321 a holding ground which extends back over the control conductor 276 to maintain the connector marked as busy to the link 200 and to 10 the selectors in the group which includes the selector 535.

The release and restoration of the manual equipment used in setting up the connections between the substations MA and P is accomplished in a manner similar to the method described above. The release of the automatic equipment is accomplished as a result of the removal of the plug 455 from the jack 459. This causes the release of the line and release relays and the restoration of the wipers of the associated connector in a well known manner. Release relay R310, upon restoring, removes the holding ground potential at the contacts 321 from conductor 276, thus causing the selector 25 535 to restore its wipers to normal in a well known manner and rendering the trunk circuit 530 available for other calls.

Connection from the automatic substation P to the manual substation M

When a call is initiated at the automatic substation P, a loop circuit is completed over the line L300 which causes operation of the line relay R395. This circuit extends from ground by way 35 of the contacts 391, the conductor 380, the closed loop at the substation P, conductor 381, contacts 382 and the winding of the line relay R395 to HV battery. The line relay R395 operates to close, at its contacts 386, a circuit for applying ground potential to the sleeve conductors of the line 300a extending to jacks at the operators' positions in the switchboard of Fig. 1, including the jack 159, for marking the line 300a and the associated line L300 as busy to incoming calls from the manual switchboard. The control conductor 382 is also grounded by the closure of the contacts 388, which marks the lines L300 and 40 300d as busy in the banks of the connectors. The operation of the line relay R395 also closes the contacts 388 to apply LV battery potential by way of the winding of the cutoff relay R390 to the control conductor of the line 300j which extends to the banks of the finder 210. Also, the operation of the line relay R395 closes the contacts 389 to apply ground potential to the 45 start conductor 301 which extends through its associated resistor 302 to the distributor 270 to cause the distributor to choose an idle link for the use of the calling line L300. The ground upon the start conductor 301 also marks the 50 level in the vertical bank 256 in which the calling line is located. Assuming that the link 200 is the first idle link encountered by the distributor 270, the finder 210 is first caused to 55 search for the level in which the calling line is located. The vertical wiper 255 is raised step by step into engagement successively with the contacts of the vertical bank 256, until ground potential is encountered upon one of the contacts of the bank 256. In the present example, ground potential will be encountered upon the second contact which terminates the grounded conductor 301. The distributor then controls the 60 finder 210 to search in the selected level for the contacts terminating the calling line, this line 65 70 75 80 85 90 95

being marked with LV battery. When the wipers of the finder 210 reach the contacts corresponding to the calling line, the control wiper C will encounter LV battery potential upon the contact terminating the C conductor 326 of the line 300₁, which causes the finder to select the calling line and extend the connection to the selector 220 of the line 200. The finder 210, which is preferably of the well-known Strowger type, in extending the connection to the selector 220, causes the switching relay R230 to be operated and close the contacts 231, 232, 233 and 234. The talking connection now extends through the T and R wipers of the finder 210 and through the contacts 231 and 232 of the switching relay R230 to the selector 220. At the contacts 233, ground potential is put upon the control wiper C, to operate the cutoff relay R390 and to mark this line as busy to incoming calls. The relay R240 is also operated to apply, at contacts 241, ground potential to the control conductor 242, thereby holding the switching relay R230 operated by way of the contacts 234.

The selector 220, which is also preferably of the well-known Strowger type, responds to the first digit dialed at the calling station MA, to position the wipers 271, 272 and 273 adjacent the level of contacts corresponding to the number dialed. During the interval between the first and second digits dialed, the selector 220 operates automatically to select an idle line in the selected group of lines extending to the group of connectors in which the connector 300 is included. Assuming that the connector 300 is selected, the connection is extended thereto by way of the selector wipers 271, 272 and 273 and the conductors 274, 275 and 276 of the line 533 and the connector 300 is prepared for the second and the final digits. When the selector 220 is seized, the release relay R250 is operated to complete, at the contacts 251, a circuit for extending multiple ground potential over the control conductor 242 to maintain the switching relay R230 operated, and, at contacts 252, the control conductors 242 and 276 are connected together. Upon receiving the second digit, the connector 300 responds to select the level or group of lines in which the called line is located. The final digit causes the wipers 371, 372 and 373 to select the contacts in the connector bank which terminate the desired line, which, in the present example, is the line 100d and the connected line L100. The functions of the connector 300 with respect to encountering a busy condition upon the line 100d, and with respect to switching through to the line L100 if the line is idle, need not be described as they are the same as those described in connection with making a call from the substation MA and through the cord 40 to the substation P. The train of switches including the finder 210, the selector 220, and the connector 300, is held operated by the ground which is applied to the control conductors 276, 325 and 242 at the contacts 321 and 322 upon the operation of relay R310 in the connector 300.

When the connector 300 has selected the line 100d by moving the wipers 371, 372 and 373 into contact with the terminals which terminate the conductors 377, 378 and 379 of the connecting line 100d, a busy test is made to determine if the associated line L100 is in a busy condition. If the line L100 is busy, ground potential will be found upon the conductor 379 of the line 100d. This ground potential will be applied to conductor 379 through the winding of the sleeve re-

lay R120, the associated plug 102 and the jack 101 if the line L100 is the calling line; or through the winding of the sleeve relay R150, the associated plug 155 and the jack 156 if the line L100 is the called line in a manual connection; or by way of the cordless B board if the operator thereat extended a call to the line L100; or through the associated contacts 365 and the wiper 373 of another connector 300 if the line L100 is called by another automatic subscriber. The busy relay R330 is operated from ground on the conductor 379 over the control wiper 373 and connects, at the contacts 324, busy tone to the talk conductor which extends through the selector 220 and the finder 210 to the calling line L300 and the substation P. Assuming, however, that the connecting line 100d is idle when called, the control wiper 373 encounters LV battery upon the control conductor 379, which battery shunts the winding of the busy relay R330 which therefore does not operate. When the switching relay R360 operates shortly after the busy test to close the contacts 361 and 362 and connect the line conductors 377 and 378 to the ringing leads through the contacts 341 and 343, this switching relay also applies, at the contacts 365, ground potential to the control conductor 379. The ground upon the control conductor 379 marks the line L100 as busy to the connectors having access to the line 100d. Also, the ground upon the conductor 379 is cross-connected at the intermediate distributing frame IDF-2 to the sleeve conductor of the line 100e which conductor terminates upon an A terminal of the main distributing frame MDF. The sleeve conductors of the lines 100a and 100f are also connected to the sleeve terminals of the main distributing frame MDF and the ground upon the sleeve of the jack 156 thus marks the line 100a as busy to the operators at the switchboard shown in Fig. 1, and the line 100f is marked as busy by the ground placed upon the sleeve conductor which cooperates with the cordless B board 440 to mark this line busy to the operators at this board. When the switching relay R360 operates and connects the line conductors 377 and 378 to the ringing leads by way of the contacts 341 and 343, ringing current is transmitted to signal the subscriber at substation M from battery, the interrupted ringing generator GEN, the upper winding of the ring cutoff relay R340, the contacts 341 and 361, the wiper 371, the tip conductor 377 of the line 100d, the line 100e, the line L100, the ringer at the substation M, and returning by way of the ring conductor of the line L100, the line 100e, the line 100d, the ring conductor 378, the wiper 372, and the contacts 362 and 363, to ground. When the subscriber at substation M answers the call, a direct current loop circuit is completed and causes the ring cutoff relay R340 to operate and open its contacts 341 and 343 to terminate the ringing signal. The relay R340 also completes a locking circuit for its lower winding (not shown) and, at its contacts 342 and 344, it completes a talking circuit from the calling substation P to the called substation M. With the wipers 371 and 372 in contact with the contacts terminating the conductors 374 and 375, a communication connection is completed between the substations P and M, which connection may be followed from the station P by way of the lines L300 and 300j, the finder 210, the selector 220, the connector 300 and the lines 100d, 100e and L100. The ground upon the sleeve conductor of the line 100a causes the cutoff relay

R110 to operate and open, at the contacts 111 and 112, the circuit for operating the line relay R115.

Method of converting a manual subscriber's line to automatic operation

The operations thus far described are those which are based on the assumption that the manual systems illustrated in Figs. 1 and 4 are still entirely manual in operation and that they have been connected with the automatic system shown in Figs. 2, 3 and 5 which may have replaced an old manual system or be merely an addition to the manual system disclosed, appropriate changes in polarity in the manual system and changes in voltage in the automatic system having been made, according to the present invention, to permit the two types of systems to be interconnected and to allow the extension of calls from one portion of the composite system to another.

Consideration will now be given to the operation of the composite system disclosed when a manual portion of the system is gradually converted to automatic operation. It will be assumed that the manual system shown in Fig. 4 is to be thus converted to automatic operation while maintaining its operative connections with the manual system of Fig. 1 and the automatic system of Figs. 2, 3 and 5.

In converting a manual line such as the line L400 to full automatic operation, the manual substation instrument at the substation MA is replaced with an automatic type instrument which includes an impulse transmitting dial. At the manual switchboard, the answering jack 401, the line 400b, the manual line circuit 405, and the line 400c are disassociated from the line L400, by disconnecting the line 400b from the E terminals of the intermediate distributing frame IDF-1, and by disconnecting the line 400c from the D terminals of that intermediate distributing frame. In the automatic switchboard the line circuit 501 is associated with the line L400 by connecting the previously installed line 400h which extends from the line circuit 501 to the F terminals of the intermediate distributing frame IDF-2, and by connecting to the F terminals of the intermediate distributing frame IDF-2 the previously installed line 400j which then extends from the terminals of the IDF-2 to the bank terminals of the line finder 210.

The above changes are of minor nature and involve no alterations or additions of equipment and are quickly and easily made without interruption of telephone service longer than the time required to replace the manual telephone instrument with the automatic instrument at the substation MA and the brief interval required to remove the lines 400b and 400c and to connect the lines 400j and 400h.

Completing connection from the converted substation MA to the automatic substation P

In initiating a call at the converted substation MA, just referred to, the telephone is removed from the hook switch, which completes a loop circuit extending over the lines L400, 400e and 400h to cause operation of the line relay R520. This circuit may be traced from ground, upon the contacts 511, by way of the tip conductor of the line 400h, over the tip conductor of the lines 400e and L400, through the completed loop at the substation MA, over the ring conductors of the lines L400, 400e and 400h, through contacts 512 and the winding of the line relay R520 to

HV battery. In operating, the line relay R520 completes, at its contacts 521, a circuit for applying ground potential to the sleeve or control conductors of the lines 400h, 400e, 400f and 400a, the sleeve or control conductors of these lines being connected together at the distributing frames as shown. The ground upon the sleeve of the line 400f marks the line L400 as busy to operators in the switchboard of Fig. 1 having access thereto by way of the jack 158, and ground upon the sleeve of the line 400a marks the line L400 busy to the operators in the switchboard shown in Fig. 4, having access thereto by way of the jack 456.

When the sleeve or control conductor of the line 400h is grounded, the sleeve conductor of the line 400d is also grounded through the cross-connections at the intermediate distributing frame IDF-2, extending between the F and G terminals. The grounding of the sleeve or control conductor 376 of the line 400d marks the connecting line 400d as busy to the connector switches in the automatic system. The lines 400d and 400e are cross-connected between the F and G terminals of the intermediate distributing frame IDF-2, which connection effectively marks the line L400 as busy to the connectors as stated above. Upon the operation of the line relay R520, the contacts 522 are opened, thereby removing LV battery potential through the relay R510 from the sleeve conductors of the lines 400h, 400e, 400a, 400f and 400d; this battery, prior to its removal at the contacts 522, marked the above lines as idle to their respective points of access, as described. At the same time, the contacts 523 are closed to apply LV battery potential through the cutoff relay R510 to the control conductor 426 of the line 400j, which extends to the finder bank contacts of the finder 210 corresponding to the calling line L400. It will be noted that the talking conductors of the lines 400j and 400e are connected together at the F terminals of the intermediate distributing frame IDF-2 and that the talking conductors of the lines 400e and L400 are connected together at the A terminals of the main distributing frame MDF. The application of LV battery potential to the conductor 426 of the line 400j marks the line L400 as the calling line in the finder banks, whereby the finder is caused to select the line 400j which is associated with the line L400.

The contacts 524, upon closing, in response to the operation of the line relay R520, complete a circuit over the conductor 403 for starting the distributor 270, which selects an idle link for the use of the calling line. The operation of the distributor 270 and the finder 210 to select the calling line 400j appearing in the finder bank is well known and briefly described in explaining the extension of a call from the substation P to the converted substation M, so that it need not be described in detail. Also, the progress of the call through the finder 210, the selector 220 and the connector 300 to select the connecting line 300d which is associated with the line L300 will not be described in view of the previous description given of a call through these switches.

In making calls through the automatic system and, more specifically, when the wipers of the connectors are rotated over the contacts of a level in search for the contacts of the called line, the wipers may pass over a number of contacts which are associated with idle lines. The control wiper of the connector, in passing over the contacts of idle lines, applies LV battery po-

tential to these contacts as these contacts are passed over by way of LV battery which is fed from the conductor 117 through the busy relay R330 and by way of the contacts 363 and 352 to the control wiper 373 and to the control contacts being contacted. As stated above, the control conductors are connected through the various distributing frames and lines to the cutoff relays associated with the lines. With the busy relay R330 connected to LV battery, it will be seen that there will be no potential difference between the battery connected to the busy relay R330 and the battery-connected cutoff relays in the line circuits. Therefore, as the connector control wiper successively makes contact with the control contacts of lines in passing over, the busy relay R330 and the cutoff relays of the lines will not be falsely operated.

However, if the busy relay R330 were connected to HV battery potential while a cutoff relay, for example, such as the manual cutoff relay R110, is connected to LV battery potential, then, upon movement of the control wiper 373 into contact with the bank contact which terminates the conductor 379 (assuming these contacts are on the same level and precede the contacts 382), there would be a potential difference between the LV battery upon the cutoff relay R110 and the HV battery upon the busy relay R330. This circuit extends from the LV battery potential upon the relay R110, from the conductor 117, by way of the winding of the relay R110, the sleeve conductors of the lines 100c, 100a, 100e and 100d, the conductor 379, wiper 373, contacts 352, 363 and the winding of the busy relay R330 to HV battery potential. From the foregoing, it will be seen that with both the relays R330 and the cutoff relays of the line circuit connected to the same battery potential, these relays are prevented from false operation when the control wiper 373 encounters the control conductors of line circuits.

The release of the connection between the converted substation MA and the automatic substation P need not be described in detail since it is effected in the manner usual to the release of connections of lines in an automatic telephone system. With respect to the release of the switch train, however, it is noted that the control conductors 276 and 325 are disconnected at the contacts 321 and 322 when the release relay R310 is restored and, likewise, that the control conductors 242 and 276 are disconnected at the contacts 251 and 252 when the release relay R250 is restored. This arrangement whereby the control conductors 276 and 325 are disconnected acts, upon release of the connector 300, to prevent ground potential from being conducted over these control conductors in series to the control wiper 373 during its return to normal position. Ground potential upon the conductor 325 during the period of release of the connector might cause improper operation of certain apparatus, such as the switching relay R360 and the cutoff relays in line circuits which may be momentarily connected upon restoration of the connector 300.

From the foregoing description of how a manual line is converted to a line of the automatic type, as applied to the line L400, it will be seen that the line L100 may also be converted to automatic operation by replacing the substation instrument at the substation M with a substation of the automatic type, by disconnecting the lines 100c and 100b from the intermediate distributing frame IDF-1 and by connecting the lines 100h, 100j to the F terminals of the intermediate dis-

tributing frame IDF-2 in a manner similar to that by which the line L400 and its associated lines are connected when the line L400 is converted to automatic operation.

5 *Connection from the automatic substation P to the converted substation MA*

In completing a connection from the substation P to the substation MA, after the substation MA has been converted to automatic operation, the operation of the switching apparatus is similar to that described in connection with a call from the substation P to the substation M. However, in making a call to the substation MA, the manual line circuit 405 (Fig. 4) is disconnected and the line circuit 501 (Fig. 5) is connected to the lines 400d and 400e in accordance with the conversion plan described above. When the wipers of the connector 300 come into engagement with the contacts terminating the conductors 374, 375 and 376 of the line 400d, and the switching relay R360 operates, ground is applied by way of the contacts 365 and the wiper 373 to the sleeve conductor 376 of the connecting line 400d. Ground potential on the conductor 376 is extended through the cross-connections at the intermediate distributing frame IDF-2 to the sleeve conductors and ground is thereby extended through the contacts 522 and the winding of the cutoff relay R510 to LV battery. The cutoff relay R510 operates to interrupt, at its contacts 511 and 512, the circuit for energizing the line relay R520. The ground potential on the control conductor 376 of the line 400d is extended to the sleeve conductor of the line 400e by way of the intermediate distributing frame IDF-2 and this sleeve conductor is connected to an A terminal of the main distributing frame MDF which also terminates the sleeve conductors of the lines 400f and 400a. Thus, the line L400 is marked busy at the jacks 158 and 456 to the operators at the switchboards shown in Figs. 1 and 4. The method of releasing the above connection is the same as that conventionally practiced in automatic telephone systems, and the apparatus for restoring the switches used in making the connection has not been shown for this reason.

Although one embodiment of the improved telephone system and certain examples of the improved method of conversion from manual to automatic operation have been shown and described by way of illustration, it will be understood that the improved system is capable of other embodiments and that the improved method may be practiced in various ways without departing from the scope of the appended claims.

I claim:

1. In a communication system, a manual telephone system including manual lines terminating in jacks at operator controlled switchboards, said jacks each including a sleeve element whereon the busy condition of the associated line may be marked by the presence of a characteristic potential, cord circuits at said switchboards having plugs for engagement with said jacks, means in said cord circuits including said plugs for applying said characteristic potential to a sleeve element of said jacks, an automatic telephone system including line selecting switches having sets of contacts for terminating lines of both said automatic and said manual systems, said sets of contacts each including a control contact whereon the busy condition of the associated line may be marked by the presence of a characteristic potential which is substantially different from the first-mentioned characteristic poten-

tial, means in one of the telephone systems for altering its busy characteristic potential to render it substantially the same as the busy characteristic potential of the other system, and means for interconnecting the two telephone systems.

2. In a telephone system, a manual system including manual lines terminating in jacks at operator controlled switchboards, said jacks each including a sleeve element, cord circuits at said switchboards having plugs associated therewith for engagement with said jacks, means in said cord circuits and including said plugs for connecting a first characteristic busy potential to said sleeve elements of said jacks, an automatic system including line selecting switches and a plurality of automatic lines, said line selecting switches having contact sets terminating said automatic lines and said manual lines, said contact sets each comprising a pair of line contacts and a control contact, means in each of said line selecting switches and including said control contacts for marking said automatic lines as busy by applying a second characteristic potential upon said control contacts, said first characteristic potential being of opposite polarity to said second characteristic potential, means in one of the systems for changing the polarity of the characteristic potential of that system to agree with the polarity of the other system, and means for interconnecting the two systems together.

3. In a communication system, a manual telephone exchange having manual lines terminating in jacks, cord circuits at said exchange having plugs for engagement with said jacks, a group of manual line circuits each associated with one of said manual lines, a first power source connected to said manual exchange, an automatic exchange having line selecting switches terminating automatic lines, a group of automatic line circuits each associated with one of said automatic lines, a second power source connected to said automatic exchange, means for interconnecting said exchanges to permit calls to be completed between said exchanges, said first power source being normally connected to said manual exchange with its polarity in opposed relation to that in which said second power source is connected to said automatic exchange, and means for altering certain connections of said first power source to said manual exchange to cause the polarity of corresponding lines in the two exchanges to agree.

4. In a communication system, a manual telephone exchange having manual lines terminating in jacks, cord circuits at said exchange having plugs for engagement with said jacks, a group of manual line circuits each associated with one of said manual lines, a first power source connected to said manual exchange, an automatic exchange having line selecting switches terminating automatic lines, a group of automatic line circuits each associated with one of said automatic lines, a second power source connected to said automatic exchange, means for interconnecting said exchanges to permit calls to be completed between said exchanges, said first power source being normally connected to said manual exchange with its polarity in opposed relation to that in which said second power source is connected to the automatic exchange, and means in the manual exchange for altering connections to certain apparatus in the manual exchange including said first-named line circuit connections to cause the polarities of corresponding parts of the associated apparatus in the two exchanges to agree.

5. In a communication system, a manual telephone exchange including a plurality of manual lines terminating in jacks, a group of manual line circuits each associated with one of said manual lines, cord circuits at said exchange provided with plugs for engagement with said jacks, control apparatus in said cord circuits including relays for controlling supervisory devices, a first power source at said exchange connected to said line circuits and to said control apparatus including said relays, an automatic exchange comprising automatic lines and switches for completing connections to said automatic lines, a group of automatic line circuits each associated with one of said automatic lines, a second power source connected to said switches and to said automatic line circuits, the polarity of said second power source being normally connected in opposite relation to that in which said first power source is connected, means for interconnecting the two exchanges comprising connecting lines corresponding to said manual lines and said automatic lines of the two systems to permit the lines in each exchange to call the lines in the other exchange, said connecting lines being associated with said jacks and with said automatic switches and comprising two line conductors and a control conductor, and means in said manual exchange for altering the polarity of the connections of said first power source to said relays and to certain parts of said manual line circuits, thereby causing corresponding connected lines in the two exchanges to have the same polarity.

6. In a communication system, a manual telephone exchange, a plurality of manual lines terminating in jacks, cord circuits at said exchange provided with plugs for engagement with said jacks, said jacks each comprising two line elements and one control element, line and control apparatus in said cord circuits, a manual line circuit associated with each manual line, a first power source connected to said control apparatus in each of said cord circuits and each of said manual line circuits, an automatic telephone exchange comprising a plurality of automatic lines and automatic line selecting switches terminating said automatic lines, said automatic switches each including a set of line terminating contacts each associated with one of said automatic lines, each set of said contacts comprising two line contacts and one control contact for each automatic line, a second source of power different in potential and opposite in polarity from said first power source and connected to apparatus in said line selecting switches, an automatic line circuit associated with each of said automatic lines, means for interconnecting said two exchanges comprising connecting lines corresponding to the manual lines and to the automatic lines in the two systems through which the lines in each exchange have access to the lines in the other exchange, said connecting lines each including two line conductors and a control conductor which are adapted to be connected with said jack elements in said manual exchange and said line terminating contacts in the automatic exchange, means in said manual exchange for reversing the polarity of said first power source connected to points in said line and control apparatus in said cord circuits and to said manual line circuits, and means in said line selecting switches in the automatic exchange for altering the potential applied to apparatus therein and to said automatic line circuit.

7. In a communication system, a manual telephone exchange having a plurality of manual lines

each terminating upon a set of manual line terminating contacts and a jack, cord circuits at said manual exchange each provided with plugs for engagement with said jacks, each plug including two line elements and one control element, line and control apparatus in each cord circuit, a manual line circuit associated with each manual line, a power source connected to said line and control apparatus in said cord circuit and to each of said manual line circuits, an automatic exchange having a plurality of automatic lines, a plurality of automatic line selecting switches having contacts upon which said automatic lines terminate, an automatic line circuit associated with each of said automatic lines, a second source of power connected to said automatic switches and to said automatic line circuits, said second source of power being different in potential and opposite in polarity from said first source of power, a plurality of first connecting lines each associated with contacts in said automatic switches and with a corresponding one of said manual line terminating contacts, an automatic jack in the manual exchange for each automatic line, a plurality of second connecting lines each associated with one of said automatic jacks and with one of said automatic lines, means in said manual exchange for reversely connecting the polarity of said first power source to said line and control apparatus in said cord circuits and to each of said manual line circuits to agree with the polarity of the connections of said second power source, and means in said line selecting switches for altering the potential of said second power source connected to apparatus in said switches and to said automatic line circuits to agree with the potential of said first power source.

8. In a communication system, a manual exchange including a plurality of lines terminating in three-element jacks, a two-conductor cord circuit comprising two element plugs together with supervisory equipment and control equipment, said plugs being adapted to engage with said jacks to answer and extend calls, a manual line circuit for each of said lines, a first power source connected to said supervisory equipment and control equipment and to said manual line circuits, an automatic exchange including a plurality of automatic lines terminating in contact sets of automatic switches, an automatic line circuit for each of said automatic lines, a second power source connected to said automatic switches and to said automatic line circuits, and means including three-conductor connecting lines for connecting together said two exchanges by connecting said manual lines with contacts of said automatic switches and by connecting said automatic lines to corresponding elements of said jacks in said manual exchange, said first power source being connected to said manual line circuits and to said supervisory and control equipment in said manual exchange with its polarity in agreement with the polarity of said second power source connected to said automatic switches and said automatic line circuits.

9. In a communication system, a manual exchange including a plurality of manual lines terminating in line terminating contacts and in three-element jacks, a three-conductor cord circuit comprising three-element plugs connected with supervisory equipment and control equipment, said plugs being adapted to engage with said jacks to answer and extend calls, a manual line circuit for each of said manual lines, a first

power source connected to said supervisory and control equipment and to said manual line circuits, an automatic exchange comprising automatic switches having contact sets at which a plurality of automatic lines terminate, an automatic line circuit for each of said automatic lines, a second power source connected to said automatic switches and to said automatic line circuits, an automatic three-element jack at said manual exchange for each of said automatic lines, means including three-conductor connecting lines for connecting together said line terminating contacts of said manual lines with corresponding contacts of said automatic switches, other connecting lines for connecting said contacts of said automatic switches with corresponding elements of said automatic jacks in said manual exchange, said first power source being normally connected to said equipment in the manual exchange with its polarity in opposition to that of said second power source connected to said automatic switches and said automatic line circuits, and means in said manual exchange for reversing said first power source connections to said equipment in said manual exchange to agree with the polarity of said power source connected to said automatic switches and said automatic line circuits.

10. In a telephone system comprising a manual exchange, an automatic exchange, and connecting lines for interconnecting apparatus in the manual exchange with related apparatus in the automatic exchange, said manual exchange comprising a plurality of manual lines, a manual line circuit for each manual line, an operator switchboard, and a first power source in said manual exchange for operating said manual line circuits and apparatus in said operator switchboard, said automatic exchange comprising a plurality of automatic lines, an automatic line circuit for each automatic line, and an automatic switchboard, said automatic switchboard including apparatus operable in connection with related apparatus in said manual exchange over said connecting lines, and a second power source for operating apparatus in said automatic switchboard which is of substantially the same voltage as that of said first power source.

11. In a telephone system comprising a manual exchange, an automatic exchange, and connecting lines for interconnecting apparatus in the manual exchange with related apparatus in the automatic exchange, said manual exchange comprising a plurality of manual lines, a manual line circuit for each manual line, an operator switchboard, and a first power source in said manual exchange for operating said manual line circuits and apparatus in said operator switchboard, said automatic exchange comprising a plurality of automatic lines, an automatic line circuit for each automatic line, and an automatic switchboard, said automatic switchboard including cooperating apparatus operable in connection with related apparatus in said manual exchange over said connecting lines, and a second power source for operating apparatus in said automatic switchboard which is of substantially the same voltage as said first power source, additional apparatus in said automatic exchange, a second power source of substantially the same voltage as that of said first power source for operating said cooperating apparatus in said automatic exchange, and an additional power source for operating said additional apparatus.
